ELECTRICAL DELAY DEVICE

Albert H. Taylor, Prince Georges County, Md.

Application January 22, 1946, Serial No. 642,780

4 Claims. (Cl. 171—97)

(Granted under the act of March 3, 1883, as
amended April 30, 1928; 370 O. G. 757)

1

This invention relates to electrical delay devices and has particular reference to electrical delay devices for the protection of electronic tubes by preventing the premature application of high potentials to the tube elements.

An object of the present invention is to provide a device capable of delaying the application of high voltage to electronic tube elements until the filaments of said tubes have warmed up properly.

Another object of the invention is to provide a means whereby the delay in closing two inter-related electrical circuits is rendered independent of the time elapsed between repetitive cycles of the system.

Still another object of the present invention is to provide a device which can be used for producing a delay between two sequential electrical phenomena the duration of which is closely controllable in time.

Still further objects of the invention reside in the details of construction wherein is provided, through this invention, a safety device for the introduction of an electrical delay which is unaffected, in respect to time duration produced, by external conditions such as temperature or pressure.

Other and further objects and features of this invention will be apparent from the following specification and drawing, showing one exemplary embodiment of the invention in which the drawing is a schematic diagram of the circuit.

In general it may be stated that the invention described herein has, as a specific illustrative use, the function of delaying the application of high voltage to the plates of rectifier or transmitter tubes until the filaments of said tubes have warmed up. This delay, in the present invention, is independent of the time elapsed since the tube filaments were last turned on. This embodiment of the invention uses a synchronous motor which begins operation at the time the filaments are turned on. After a time dependent upon the motor speed and switch contacts, which may be made controllable, a switch driven by the motor closes and permits power to be supplied to the high voltage transformer or to a utilizing agency, either directly or through a relay, simultaneously opening the power supply to the motor circuit and causing the motor driven switch to be stopped in such a position that the high voltage power supply circuit is closed until such time as either the high voltage switch itself is opened or the filament power switch is opened. When the filament supply is shut down

2

and then turned on again, or if temporary power failure occurs the plate voltage cannot be applied until the motor-driven switch has made another complete revolution.

- 5 In the circuit illustrated, alternating current is supplied from an external power source. Switch 1 is a double pole-single throw switch which controls the power supplied to the filament transformer. A pilot light 2 is shunted across the filament transformer primary circuit to indicate when power is supplied to this circuit. Connected to one side of the power supply is a synchronous motor 3 which is coupled with respect to its other input terminal both to contact 15 24 of a rotary switch and to contact 12 of relay 7. The rotatable element 4 of said switch is mechanically linked through shaft 11 with the synchronous motor 3. The contact element 5 of said rotary switch is caused to rotate by the 20 motion of the shaft in such a manner that contacts 24, 25, and 26 are engaged successively. The width of rotor 5 is such that contact 25 is made before contact 24 is broken but contact 26 is further away from contact 25 in angular degrees than the width of rotor 5, so that contact 26 is not made until contact 25 is broken. Upon further rotation, however, the electrical connection of contact 5 with contact 25 is disengaged and contact with terminal 26 is made. 25 30 From said rotary switch, connections are made in the manner indicated below:

Rotation contact 5 is connected to one line of the power source and to the moving contact 16 of relay 7. Contact 24 is connected with the 35 synchronous motor as described above. Contact 25 is connected with the moving contact 23 of relay 8. Contact 26 is connected to the junction between contact 19 of relay 8 and to one terminal of the energizing coil of relay 8.

- 40 Two relays, 7 and 8, each having two armatures, are utilized in this circuit. In the de-energized position of relay 7 movable contact 16 provides electrical continuity with contact 12 and movable contact 17 with contact 14. In the 45 energized position of said relay, contacts 13 and 15 are provided electrical continuity with movable contacts 16 and 17 respectively.

In a like manner, relay 8 is so constructed that in the de-energized position movable contact 22 provides electrical continuity with contact 18 and movable contact 23 with contact 20. In the energized position of said relay, contacts 19 and 21 are provided electrical continuity with movable contacts 22 and 23 respectively.

55 Opposite terminals of the windings of relay 7

and 8 are connected to one side of the power source through a safety door or interlock switch 6.

In addition to the connections enumerated above, a pilot lamp 9 is connected in series with contact 13 and one lead of the output to the 5 plate transformer primary or to any load device. A double pole-single throw switch, 10, is provided in the plate transformer lead as shown in the figure.

Assuming the device to be so constructed, its 10 operation will be as follows:

Upon connection of the invention with power supplies as indicated and with power-consuming means as exemplified by the primary of a filament transformer and the primary of a plate transformer, no power will be supplied to the circuit elements involved until switch 1 is closed. This immediately energizes the primary of the filament transformer and turns on pilot light 2. Power is connected to the motor 3 through contacts 12 and 16 of relay 7. Both relays 7 and 8 are unenergized. It is assumed throughout the following discussion that interlock switch 6 is in the closed position. Through the rotation of contact 5 of rotary switch 4 over contacts 24 and 25, no effect occurs to either relay 7 or 8. When said moving contact reaches contact 26, however, current flows through the coil of relay 8, and such energizing effect connects contacts 22 and 23 of said relay to contacts 19 and 21, respectively. As a result, thereof, relay 8 is rendered self-locking and thus remains energized directly on the power source through switch 1 independently of the rotary switch, while rotary switch 4 continues to rotate over such an elapsed time as is deemed necessary, depending upon contact spacing and motor speed. Upon further rotation contact 5 reaches contacts 24 and 25 thereby energizing relay 7 through contacts 23 and 21 of relay 8. Upon the energizing of relay 7 electrical connection is made between contacts 17 and 15 of said relay, supplying power through switch 10 which, when closed, furnishes a path for the supply of energy to the primary of the plate transformer. Simultaneously with the closing of the aforementioned relay 7, power is supplied through contacts 16 and 13 to pilot light 9, indicating that the plate transformer primary circuit has been energized.

If, subsequent to this time, power should be withdrawn from the filament transformer both relays 7 and 8 would be immediately deenergized. When, subsequently, power was supplied the motor would again require a revolution throughout the remainder of its cycle to such a position that segment 5 must again be in contact consecutively with terminals 26, 24 and 25 as described heretofore.

It will be apparent to one skilled in the art that my invention is by no means limited to the particular organization shown and described, but that many modifications may be made without departing from the scope of my invention as set forth in the appended claims.

The invention described herein may be manufactured and used by or for the Government of the United States of America for governmental purposes without the payment of any royalties thereon or therefor.

What is claimed is:

1. An electrical delay device comprising a source of electrical power, a plurality of output circuits, first switching means operable to connect said source to one of said circuits, and second

switching means operable to connect said source to another of said circuits after operation of said first switching means, said second switching means including a pair of relays, a rotating multi-contact switch means for energizing said relays in predetermined time sequence and means operating said rotating multicontact switch means in response to operation of said first switching means.

2. An electrical delay switching means comprising a source of electrical power, a plurality of output circuits, first switching means operable to connect said source to one of said circuits, and second switching means operable to connect said source to another of said circuits, said second switching means including a switching relay, a conditioning relay for said switching relay, a rotary switching device for energizing said relays in predetermined time sequence, means initiating operation of said rotary switching device in accordance with operation of said first switching means, and means terminating operation of said rotary switching device in response to energization of said switching relay.

3. In combination, a source of power, a plurality of output circuits, switch means operable to form a connection between said source and one of said output circuits, relay operated switch means operable upon energization to form a connection between said source and another of said circuits, relay means for conditioning said relay operated switch means to be energized, a motor driven switching device operable upon operation of said switch means for effecting energization 35 of said relay means and for energizing said relay operated switch means a predetermined interval of time following energization of said relay means, and means terminating operation of said motor driven switching device in accordance with energization of said relay operated switch means.

4. An electrical delay device for selectively connecting a source of energy to a plurality of output circuits comprising first switch means operable to connect said source to one of said 45 circuits, second switch means for establishing a connection between said source and another of said circuits, conditioning means for rendering said second switch means in an operable condition, a timing device for operating said conditioning means and said second switch means in predetermined time sequence, means initiating operation of said timing device in accordance with operation of said first switch means, and means terminating operation of said timing device in accordance with operation of said second switch means.

ALBERT H. TAYLOR.
